ABSTRACT OF THE DISCLOSURE

A system for determining whether two sets of electrical signals are related to each other by a predetermined code and more particularly an apparatus for converting a first set of signals to a second set of signals including a diode matrix having first and second sets of input and output terminals for receiving the two signals to be compared and means connected to the input and output terminals for sensing the electrical condition of the matrix so that correspondence and non-correspondence between the two sets of signals produces a suitable indication.

At any particular instant in a digital computer logic system a great deal of information is stored in the computer memory and control units. In addition some word or a few words will be in transit from one place to another or are being converted from one code to another, such as a conversion from a Gray code to an Excess-3 code. Transfers and conversions of this kind present both an opportunity for circuits to fail and an opportunity for error checks to be made on the information being transferred or converted. It is well known in the digital computer art to check errors of transmission by a parity check system which utilizes an odd or even characteristic of a code. It is also known that digital code errors can be checked by an all-bit comparison or collating system in which the same code is transmitted twice and any discrepancy which arises in the comparison can then be noted.

This invention generally relates to an error checking system for digital codes. It specifically employs a selection matrix of diodes which can render a result with the same degree of precision as that of an all-bit comparison system without the need of comparing or collating all of the bits. Furthermore, the comparison system disclosed by this invention provides an extremely effective method of error checking when code conversion, or in particular, a code inversion-conversion, is required.

The primary object of this system is to provide a comparison or a collating error checking system which results in precise error check without the undue burden of comparing all of the bits being transmitted.

Other and obvious objects of this invention will be ascertained from the full description of the operative capabilities of the system which is hereafter fully described.

FIG. 1 is a block representation of the subject invention.

FIG. 2 shows a detailed schematic arrangement of the matrix of FIG. 1 together with the output gates G2 and G4.

FIG. 2a shows a detail schematic representation of the input gate G1.

FIG. 2b shows a detailed schematic representation of the input gate G3 and the gate GP.

2

Referring specifically to FIG. 1, it represents an error checking system, which may be connected in parallel to a digital converter unit, capable of converting from one code A to another code B, or vice versa. AI represents an input terminal for a code A system, such as a Gray code, and AO represents an output terminal for the same A system. The signals from these terminals are operated upon in that particular area of the digital computer system using the A code for its operations. Likewise, BI represents an input terminal for a code B system, such as an Excess-3 code, and BO represents an output terminal for the same code B system. The signals from these terminals are operated upon in the particular digital computing area which uses the B code. MX represents a matrix arrangement which can be composed of a one-sided diode arrangement; however, it is not so limited. In practice, it is usually composed of a two-sided matrix. MA represents an input and output terminal on the A side of the matrix and MB is the similar terminal on the B side thereof. G₁, G₂, G₃ and G₄ represent logic AND gate circuits provided between the above referred to inputs and outputs of the matrix and the inputs and outputs AI, AO, BI, and BO. AIC, AOC, BOC and BIC represent the input control terminals for the logic AND gate circuits. GP represents an error detection circuit and ER represents the output signal generated by this error checking system.

The operation of the error checking system will now be described. Assuming a conversion from an A code system to a B code system to be represented as A→B, and reverse conversion B→A and letting "n" represent the bits of individual codes, a Code A systems and code B systems can be identified as C_i(A) and C_j(B) (i, j=1, 2, 3 . . .). The above described matrix performs a conversion from A to B and B to A, in which correspondence of C_i(A) with C_j(B) is determined by connection between "n" number of terminals D_i corresponding to the C_i(A) and equal number of E_j terminals corresponding to the C_j(B). Assuming a code C_i(A) is provided at the input of the matrix at terminal MA from input terminal AI of the code A system through the logic AND gate circuit G₁, the corresponding terminal D_i alone will be enabled to the "1" state leaving all the other terminals D_k (k unequal to i) at the "0" state. The terminals D_i and E_j of matrix MX are connected so that a code C_j(B) corresponding to the terminal E_j is obtained at the output terminal BO, from the output terminal MB of the matrix MX through the logic AND gate circuit G₂. Under these conditions, because all the terminals D_k within the matrix are combined respectively with all the terminals E_m, (m unequal to j), the terminals E_m must indicate a "0" state. The particular connection of the D and E terminals is predetermined by the code conversion which is desired to be made.

Assuming that the matrix MX is left in the above described state and an echo code corresponding to C_j(B) is placed in the input terminal MB from input terminal BI of code system B through the logic AND gate G₃. The terminal E_j will then indicate a "1" because of the input of code C_j(B) into the matrix through MB while the remaining terminals E_m indicate "0" causing the matrix MX to disclose an identical state as though a code C_i(A) were placed at the input terminal MA on the A side of the matrix. On the other hand, if a code C_i(A) were placed in the input terminal of MA while providing the input

terminal of MB with a code $C_j(B)$ the latter not corresponding to the $C_i(A)$ code (i unequal to j) the terminal D_i will be in the "1" state reducing the remaining terminals to "0" state. This will also subsequently turn the terminal E_j to "1" because of the connection previously established between terminals D_i and E_j within the matrix.

Because the matrix has the characteristic of indicating a "0" state in case a "0" and a "1" state are overlapped, the voltage on each of the terminals E_i and D_j (i, j equal to 1, 2, 3 . . .) is reduced to a "0" state indication whenever an overlap occurs. This also reduces to a "0" state indication the input and output terminals MA and MB of the matrix MX.

The terminals MA and MB are composed of mark terminals and space terminals depending on the number of bits "n" on the codes $C_i(A)$ and $C_j(B)$ and on both mark and space terminals becoming "0" at the same time.

An arbitrary check can then be made on the code being transmitted. The error detecting circuit GP can check a simultaneous entry of "0" by any mark and space terminal and it is therefore capable of detecting an overlapping of uncorresponding code between the MA and MB input and outputs of the matrix MX. This can also be accomplished with an inversion-conversion operation.

FIG. 2, in conjunction with FIGS. 2A and 2B, discloses a particular embodiment of the invention, for purposes of clarity and description and should not be considered limiting. A three-bit one-selection diode matrix is used for convenience in place of an eight-bit double selection matrix which is generally used in practice. It must be understood that the former is shown to merely facilitate the presentation of the subject invention. FIG. 2A details a three-bit exemplary embodiment of gate G_1 , and FIG. 2B shows the details of an exemplary embodiment of gates G_3 and G_p .

A three-bit input gate or register G_1 using the $C_i(A)$ code is connected in FIG. 2A to the input terminals AI_1 , AI_2 , and AI_3 . The "1" state in this embodiment is represented by a -12 volt condition on a line and a "0" state is represented by 0 volt thereon. The input circuit connected to terminal AI_3 is composed of diodes d_1 , d_2 and resistor r_1 , which when considered together with the input control terminal AIC, constitutes a logic AND gate circuit. If an output is emitted from this AND gate, it becomes the input to transistor TS upon the base terminal thereof. The transistor TS inverts the phase of the signal received on its base and enters it as an output on its collector terminal as an inverted signal of the base input. This output is applied through diode dH_1 to terminal $A3S$ in FIGS. 2A and 2. In addition the collector output of transistor TS is again inverted through transistor TM. This transistor is connected on the output terminal of an AND gate composed of diodes d_3 , d_4 and resistor r_2 . One of the inputs to this logic AND circuit is the control signal from terminal AIC. By this circuit arrangement, the following phase relationship is achieved. The output of transistor TS at terminal $A3S$ and the input at AI_3 are in opposite phase, while the output of transistor TM at terminal $A3M$ (via diode dH_2) is of the same phase as the input of AI_3 .

Terminal A_3M in FIGS. 2 and 2A may be referred to as the "mark" terminals, while those designated A_3S may be called the "space" terminals.

Terminals AI_2 and AI_1 in FIG. 2A are connected to the same type of logic circuit arrangement as the terminal AI_3 . This type of a logic circuit arrangement gives an output at each of the mark terminals A_3M , A_2M and A_1M and at each of the space terminals A_3S , A_2S and A_1S , when the input control terminal AIC is "1." For example, assuming that an input pulse of 1, 1, 1 is entered at the terminals AI_1 , AI_2 and AI_3 while a "1" is simultaneously entered at the control terminal AIC, the resulting output at the mark input terminals A_1M , A_2M and A_3M on the A side of the diode matrix be a "1" while the space terminal on the same side of the diode matrix, that is on the A side, will be at "0." This places terminal D_7 of the

matrix at the "1" state since all three of the mark terminals are diode connected to terminal D_7 . The remaining matrix terminals D_0 through D_6 will be in the "0" state, because each is diode connected to at least one space terminal which is grounded through the respective conducting transistor at the input, causing all matrix terminals D_0 - D_6 to be at zero volts.

With the two diode matrices interconnected in the exemplary manner shown, the "1" on terminal D_7 is transferred to terminal E_1 , which is diode connected only to terminals B_3S , B_2S , and B_1M . This state of the diode matrix results in the mark terminals on the B side of the matrix indicating a 0, 0, 1 code whereas that of the space terminals conversely indicate a 1, 1, 0 code. The phase or "1" state of the above input pulse entered on space terminal B_3S is reversed by transistor TA, and it becomes a "0" output which is transmitted to a logic AND gate circuit composed of diodes D_5 , D_6 and resistor r_5 . An output results at $B0_3$ when an output control pulse is provided at the input control terminal $B0C$ on the B side of the matrix. Similar operations are made for the input pulses placed on space terminals B_2S and B_1S .

If an input control pulse "1" is placed at input control terminal $B0C$, the truth table for output terminals $B0_3$, $B0_2$ and $B0_1$ gives a coded output of 0, 0, 1 which means that a code of 0, 0, 1 is obtained in the $C_1(B)$ code of the $C_j(B)$ system corresponding to a 1, 1, 1 coded output of the $C_7(A)$ code of the $C_i(A)$ system as explained in relation to FIG. 1.

Reference is now made to gate G_3 in FIG. 2B which gate is similar in all respects to gate G_1 of FIG. 2A, except its mark and space output terminals connect to matrix side B at correspondingly designated terminals. Gate G_3 is used for code checking purposes.

By entering an input control signal of "1" at terminal I in gate G_3 (FIG. 2B) on the B side of the matrix and entering into that gate the $C_1(B)$ code resulting from gate G_2 (i.e., 0, 0, 1 at input terminals BI_3 , BI_2 , and BI_1), the encoding into a $C_j(B)$ code of the above $C_i(A)$ code is overlapped at the matrix input and output terminals B_1S , B_1M through B_3S , B_3M on the B side. This is true because an 0, 0, 1 input to gate G_3 results in only terminals B_3S , B_2S and B_1M being at "1," it will be recalled that these same terminals were at "1" in the transmission of the code from the A side to the B side. Consequently, the voltage level of terminals E_1 and D_7 remains near -12 volts, i.e., at "1." The other matrix terminals E_0 , E_2-E_7 and D_0-D_6 remain at the "0" state. These conditions of the E and D terminals cause gate G_4 to effect an output of 1, 1, 1 at terminals $A0_3$, $A0_2$, $A0_1$ when an input pulse of "1" is applied to control terminal $A0C$. Since gate G_4 provides the same output as the input applied to gate G_1 , the original signals were transmitted without error.

Assuming that an encoded signal other than the 0, 0, 1 is applied at the input terminals BI_3 , BI_2 and BI_1 , a different result is achieved. For example, if a 0, 0, 0 code is applied at the gate input terminals BI_3 , BI_2 and BI_1 , matrix input terminals B_3S , B_2S , B_1S would be at "1," which should cause terminal E_0 to be at "1" reducing the other terminals E_1 through E_7 to a "0." However, terminal D_0 on the A side of the matrix is at "0" because of the 1, 1, 1 code applied at the input terminals AI_3 , AI_2 and AI_1 . Because a "0" state will override a "1" state, terminal E_0 which is connected to terminal D_0 also results in a "0" state. In like manner, the "0" condition of terminal E_1 caused by the 0, 0, 0 signal to terminals BI_3 , BI_2 , BI_1 , causes terminal D_7 to be in the "0" state also.

In other words, terminals D_0 through D_7 and E_0 through E_7 within the matrix are all reduced to the "0" state indicating that if codes A and B do not correspond with each other, all of the memory interconnections are registering a "0" state, which reduces all of the mark and space terminals on both the A and B sides of the matrix to the "0" state. The mark and space terminals connected to

the D_0 through D_7 and E_0 through E_7 terminals of the matrix, are at the "0" level and simultaneously register a "0" state level, only when all of the terminals D_0 through D_7 and E_0 through E_7 are at the "0" level. Outputs at $A0_3$, $B0_3$ through $A0_1$, $B0_1$ are all "0" when the A and B codes do not correspond. While time coincidence of applying the input signals AI_3 , AI_2 , AI_1 , and BI_3 , BI_2 , BI_1 to the respective matrices is not basically necessary, it may be assured when the two gating control signals AIC and BIC are simultaneously timed. This assures that they will be on or off at the same time so that the comparison determination of the related input code signals will be effectuated and any false comparison signal possibility will be eliminated.

From this logic arrangement an erroneous code transmission can be checked by providing a detection circuit G_p (see FIGS. 1 and 2B) composed of diodes dE_1 and dE_2 , resistor rE and a transistor TE . This detection circuit constitutes a NOT AND circuit, which has an output of "1" at its ER terminal only when both input terminals BIM and BIS are at the "0" level. Since this is a condition which never happens for any pair of mark and space terminals unless there is an error in the A and B codes, a simple accurate error detector is provided.

The error detection circuit described above is of course, applicable not only to the specific terminal combination of BIM and BIS as described, but also to any other pair of mark and space terminals on either side of the matrix.

As hereinabove described, when a matrix is employed in an A to B conversion, detection of conversion errors can be precisely determined by overlapping the encoding comparison codes from the B side of the matrix which is also logically applicable to the identical comparison from the B to A side thereby allowing the detection of errors in an inversion comparison system.

The foregoing construction and advantages of this error checking system are readily apparent. Numerous modifications will readily occur to those skilled in the art, after a consideration of the specification and accompanying drawings. It is not intended to limit the invention to the precise embodiment shown and described, but all suitable modifications and equivalents may be readily resorted to if desired.

What is claimed is:

1. A system for determining whether two sets of electrical signals are related to each other by a predetermined code, comprising:
matrix means having first and second sets of input and first and second sets of output terminals for respectively receiving said two signals to effect comparison therebetween,
said matrix being internally interconnected in accordance with said predetermined code, and
means connected to one of said input and connected to one of said output terminals for sensing the electrical condition of said matrix means as between at least two different conditions, to indicate correspondence and non-correspondence between said sets of signals.
2. A system as in claim 1 including:
plurality of gating means connected to said first and second input and output terminals of said matrix means for respectively impressing said two signals upon said matrix means for effecting comparison therebetween.
3. A system as in claim 1 wherein said means connected to one of said input terminals and connected to one of said output terminals for sensing the electrical condition of said matrix means indicates non-correspondence between said sets of signals only when both said sets are in a "0" logical condition.
4. A system as in claim 3 wherein said means for sensing the electrical condition of said matrix consists of a NOT AND logic circuit.

5. A system as in claim 2 wherein said plurality of gating means includes of AND logic circuits.

6. A system for determining whether two sets of electrical digital signals are related to each other by a predetermined code, each of said sets including a plurality of complementary signal pairs, comprising:

first matrix means having a plurality of pairs of input terminals for receiving one of said sets of signals pair-to-pair,

second matrix means having a plurality of pairs of input terminals for receiving the other of said set of signals pair-to-pair,

means interconnecting said first and second matrix means at their outputs in accordance with said code to cause at least one pair of terminals of at least one of said matrix means to be in a given electrical condition only if said two sets of signals are not actually related by said code, and

error detector means connected to said one pair of input terminals for sensing said electrical condition when it occurs and then indicating non-correspondence between said input signals.

7. A system as in claim 6 including:

first plurality of gating means connected to said plurality of pairs of input terminals of said first matrix means, for impressing a first set of electrical digital signals upon said first matrix means, and

second plurality of gating means connected to said plurality of pairs of input terminals of said second matrix means, for impressing a second set of electrical digital signals upon said second matrix means.

8. A system as in claim 6 wherein said error detector means for sensing said electrical condition indicate non-correspondence between said input signals only when both are in a "0" logical condition.

9. A system as in claim 6 wherein said error detector means consists of a NOT AND logic circuit.

10. A system as in claim 7 wherein said first and second plurality of gating means consists of AND logic circuits.

11. Apparatus for converting a first set of electrical signals in a first code into a second set of electrical signals in a second code comprising:

input terminal means for receiving said first set of signals,

matrix code converting means connected to said input terminal means for converting said first set of signals in said first code into said second set of signals in said second code,

matrix code reconverting means for reconverting said second set of signals in said second code into a third set of signals in said first code, and

means for comparing at least one signal of said third set of signals and the complement of said one signal and producing an error signal if said one signal and said complement of one signal do not correspond.

12. Apparatus for converting a first set of electrical signals in a first code into a second set of electrical signals in a second code comprising:

input terminal means for receiving said first set of signals,

code converting means connected to said input terminal means for converting said first set of signals in said first code into said second set of signals in said second code,

code reconverting means for reconverting said second set of signals in said second code into a third set of signals in said first code, and

means for comparing at least one signal of said third set of signals and the complement of said one signal, producing an error signal if said one signal and said complement of one signal do not correspond and causing said first, second and third sets of signals to

assume a uniform state when said first and third sets do not correspond.
